UNITED STATES PATENT OFFICE.

CHARLES FREMONT CURREY, OF TOPEKA, KANSAS, ASSIGNOR TO THE KANSAS VOTING MACHINE COMPANY, OF TOPEKA, KANSAS, A CORPORATION OF KANSAS.

METHOD OF MAKING HUBS UPON SHEET-METAL ARTICLES.

1,048,046.

Specification of Letters Patent.

Patented Dec. 24, 1912.

Application filed February 25, 1909. Serial No. 480,033.

To all whom it may concern.

Be it known that I, CHARLES FREMONT CURREY, a citizen of the United States, and a resident of Topeka, in the county of Shawnee and State of Kansas, have invented a new and useful Improvement in the Method of Making Hubs upon Sheet-Metal Articles, of which the following is a specification.

My invention relates in particular to the method of making various articles or parts used in voting machines having numerous shafts on which numerous devices, such as locking dogs, arms, etc., are mounted. And the object is to provide a simple, economical, and efficient method of making a suitable article of this kind with an integral hub, both the article and its hub being made from sheet metal.

In the drawings accompanying and forming part of this specification and in the description of the drawing, I have shown my invention in its preferred form, and have shown the best mode of applying the principles thereof; but it will be understood that my invention is not confined to the exact details of the drawing and of the description of the drawing; and that, within the scope of the appended claim I contemplate changes in form, proportions, and materials, the transposition of parts, and the substitution of equivalent members, without departing from the spirit of the invention.

Figures 1, 2, 3, and 4, respectively, are vertical center sectional views of the several dies and corresponding punches used in forming the article with the integral hub from sheet metal, each view showing also the sheet metal in the form made by the punch and die. Fig. 5 is a side view of a completed article or part with the integral hub, the part having been cut by the blanking die not here shown. Fig. 6 is a face view of the punch shown in Fig. 4, and Fig. 7 is a face view of the die shown in Fig. 4. Fig. 8 is a side view of a piece of the sheet metal with the integral hub as it comes from the last punch and die, namely, those shown in Figs. 4, 6, and 7.

Similar reference numerals indicate like or corresponding parts throughout the several views.

9 represents a strip or piece of sheet metal, and 10 is a hub formed therein and therefrom, its outer end being beveled, as shown at 11. And in Fig. 5 I have shown a device

which is adapted to be mounted on a shaft to serve both as a universal locking device and as a selective locking device in a voting machine. While any suitable material may be used for forming this article with the integral hub from sheet metal, yet I prefer to use half-hard brass because it answers all the requirements of a voting machine construction, and permits the hub to be drawn out from the sheet metal in the manner hereinafter described to form the integral sheet metal hub. The article shown in Fig. 5 is a sample only. After the hubs have been formed in the sheet metal, various forms may be punched out from the sheet metal with the integral hub, as any blanking die may be used, the hole through the hub serving as a guide for both the punch and die to insure an accurate blank with relation to the hub.

To make the article with the integral hub from sheet metal, I first subject the sheet metal to the operation of the punch and die shown in Fig. 1, 12 representing the punch and 16 representing the die. The base 20 of the punch is, it will be noted, considerably broader than the diameter of the inside of the hub which is to be finally formed, and the end of the punch is quite rounded, so that the effect is to form a dent in the sheet metal as indicated in the drawing. The article is then operated upon by punch 13 and die 17, the base 22 of this punch being narrower than the base of the first punch, but broader than the final diameter of the hub, the sides 23 being straighter, and the point 24 being longer, so as to draw out the dent at the end and bring it in at the base, as shown in the drawing. The article is next subjected to punch 14 and die 18. The punch is of uniform diameter throughout its length, as indicated at 25, except that the end 27 is slightly rounded off, as indicated at 26. This operation forms the hub in nearly its final shape but with the bottom still in. The article is next subjected to the operation of punch 15 and die 19, whose cutting edges 29 and 31 cut out the bottom 32, leaving the end of the hub beveled or rounded off as indicated at 30 in Fig. 4 and at 11 in Fig. 8. This last punch and die are adapted to shape up the hub in its final form so as to fit truly and accurately on the shaft.

Where numerous shafts are used and numerous devices are mounted on each shaft,

there is great economy in using this integral device and hub made from sheet metal and in making these devices by the method I have described, as it greatly reduces the cost of manufacturing the machine; whereas it has been customary to form these devices from sheet metal, and then make separate hubs or bushings, and then secure the devices on the bushings. But by my method, I am able to draw out a hub from the sheet metal which hub is long and suitable for a substantial bearing on the shaft for holding the article or blank rigidly on the shaft. To be more specific, I am able, by the method herein described, with No. 16 half-hard sheet brass, to draw out a hub about one-quarter inch long with an inside diameter of about seven-thirty-seconds of an inch.

What I claim is:

The method of making hubs upon sheet metal articles, consisting of first indenting the sheet metal leaving the metal outside of the indented area intact, the indentation being broader at the base than the final inside diameter of the hub, then drawing up the sheet metal around the base and spreading it out at the bottom to form an elongated substantially cylindrical hub, and then cutting off the extreme bottom.

In testimony whereof I have hereunto signed my name in the presence of subscribing witnesses.

CHARLES FREMONT CURREY.
